UNITED STATES PATENT OFFICE.

GEORGE C. NOROS, OF PHILADELPHIA, PENNSYLVANIA, ASSIGNOR TO STANDARD
PRESSED STEEL COMPANY, OF PHILADELPHIA, PENNSYLVANIA, A CORPORA-
TION OF PENNSYLVANIA.

SHAFT-HANGER.

1,195,257.

Specification of Letters Patent. Patented Aug. 22, 1916.

Application filed March 14, 1910, Serial No. 549,304. Renewed September 25, 1914. Serial No. 863,553.

To all whom it may concern:

Be it known that I, GEORGE C. NOROS,
a citizen of the United States, residing in
Philadelphia, Pennsylvania, have invented
5 certain Improvements in Shaft-Hangers, of
which the following is a specification.

My invention relates to shaft hangers, and consists of certain improvements in structures of this character made of pressed sheet metal whereby I am enabled to materially strengthen the same at a vital point.

The general construction of my hanger is substantially similar to that shown and described in the patent of H. T. Hallowell, No. 767,225, dated Aug. 9, 1904, and the feature of my present invention is the provision of reinforcing means for the purpose of strengthening the leg and foot of the hanger, particularly the junction point of such leg and foot, and the method or mode of assembling, shaping and attaching such reinforcing means with the legs. These and other features of my invention more fully described hereinafter are fully shown in the accompanying drawings, in which:

Figure 1, is a view in elevation, partly in section, of a shaft hanger embodying my invention, the sectional portion at the right being on the line $a-a$, Fig. 2, while the sectional portion at the left is on the line $b-b$, Fig. 2; Fig. 2, is a side or end elevation of the hanger shown in Fig. 1; Fig. 3, is an inverted sectional plan view on the line $c-c$, Fig. 1, of one leg and foot of the hanger; Fig. 4, is a sectional view on the line $d-d$, Fig. 1; Figs. 5, 6, 7 and 8, are sectional views similar to Fig. 3, illustrating modified constructions embodying my invention; Fig. 9, is a view of a partly finished blank from which the hanger legs are made; Fig. 10, is a sectional view on the line $e-e$, Fig. 9, showing the reinforcing plates in place; Fig. 11, is a sectional view on the line $f-f$, Fig. 10; Fig. 12, is a sectional view illustrating one step in the formation of the leg; Fig. 13, is a view illustrating a further step in the formation of the hanger comprising the substantially right angled bend of leg and reinforcing means; Fig. 14, is a longitudinal sectional view illustrating the finished shape of the leg and reinforcing means, and Fig. 15, is a sectional view of the same character as Fig. 12, showing a modification within the scope of my invention.

55 Shaft hangers of the type to which my in-

vention has been applied comprise in general legs of pressed up sheet metal, and in the present instance such legs, indicated at 1, have substantially centrally disposed longitudinal ribs 2, and terminate in feet 3. In 60 addition, the legs of my improved hanger, as shown in the accompanying drawings, may be provided with rolled edges 4. The legs may be connected at the lower ends by a cross piece 5, and at a substantially central 65 point by a cross piece 6; said cross piece carrying bolts 7, with suitable lock nuts 8 for engagement with a box 9, which, as indicated in the present instance, may be also provided with horizontally disposed position- 70 ing bolts 10. If desired, however, the hanger may be of the type illustrated in the patent of H. T. Hallowell, No. 767,223, of Aug. 9, 1904, or of a construction of the same general character in which the two legs are integral. The legs are shaped or turned outwardly by suitable dies to form the feet whereby the hanger may be secured to a beam, joist, girder or other supporting structure, and provision is made for the passage 80 of bolts through said feet for the purpose of securing the hanger in place. In the use of these hangers any lateral play occasioned by longitudinal movement of the shaft tends to strain the feet at the bolt connections and 85 cause the hanger to get out of plumb, thereby affecting its utility, and in many instances destroying its usefulness. To avoid this danger, I provide reinforcing means for use at the junction of the leg and foot, and 90 when said leg and foot are integral the reinforcing means and the leg will be bent simultaneously, thereby forming the foot and its reinforcing means on the same bend or curve. As shown in Figs. 1, 2, 3 and 4, 95 such reinforcing means consists of a plurality of plates secured to the outside of the leg by rivets 11, one of said plates, indicated at 12, extending from a point a short distance above the cross piece 6 and having the same 100 contour as the legs and foot and the bend connecting the same so as to extend under the foot, as clearly illustrated in the drawings. This strengthening plate may be of the same weight of metal as the hanger, and 105 may be hooked under the beaded or rolled edge 4 of the leg of the same. The other plate, indicated at 13, provided as additional strengthening means, may be and is preferably, as shown in the drawings, of a metal 110

heavier than the plate 12, and may be secured in place by rivets 14 which pass through the leg and also through the reinforcing plate 12. This reinforcing plate 5 may also be caught under the beaded or rolled edge 4 of the leg of the hanger. While I prefer to form the legs of the hanger with beaded or rolled edges engaging and overlying the reinforcing plates, 10 their employment is not absolutely essential, nor is it necessary that the edge be turned down into actual contact with said reinforcing plates.

In some instances, particularly when using 15 heavier metal to form the shaft hanger, I may employ a single reinforcing element for the leg and foot portion, of the same ply as the metal of the hanger, as indicated in the sectional view, Fig. 5, which bears the same 20 relation to the structure as the sectional view illustrated in Fig. 3, and in which 1^a represents the leg of the hanger, and 12^a the reinforcing plate. In other instances, the 25 heavier reinforcing means may be interposed between the wall of the shaft hanger and the thinner reinforcing member, as clearly shown in the sectional view, Fig. 6, which corresponds with the sectional views, Figs. 3 30 and 5, and in which 1^b is the shaft hanger leg, 12^b one reinforcing member and 13^b the other and heavier section.

In Fig. 7, I have shown the leg 1^c with its edges 4^a turned over against the reinforcing plate 12^a. In this instance, the metal of the 35 leg and reinforcing plate may be substantially heavy and of the same weight or gage. In Fig. 8, the leg may be provided with a flanged edge 4^b, and the reinforcing plate may be secured in place by rivets 11^c.

40 When employing the heavier metal to form the shaft hanger legs, as shown in Figs. 5 and 7, the longitudinal rib 2 may, if desired, be omitted.

After the blank and reinforcing plates are 45 assembled they are shaped by suitable dies and a depression 15 may be formed on the upper or inner side of the foot to additionally strengthen the same and afford a seat to receive a cross piece 16, which may be secured to said foot by rivets 17 in the manner clearly illustrated in Figs. 1 and 2. For 50 the passage of bolts securing the hanger in place, the foot composed of the plurality of plates may be apertured at 18, and the complete hanger may have four of such apertures, two in each foot. In other instances, 55 a single aperture may be provided, preferably centrally disposed, taking the place of the rivets 17, which in such instance would be changed to take positions occupied by the 60 apertures 18 as shown in Fig. 4. In such instance the cross piece 16 may or may not be used.

In Figs. 9 to 15, inclusive, I have shown 65 views illustrating the manner of assembling

the parts to form the shaft hanger leg and reinforcing means preparatory to shaping or forming the same by means of suitable dies. In Fig. 9, a partly finished leg blank is shown, with edge flanges turned up which 70 subsequently form the rolled or beaded edges 4. The reinforcing plates 12 and 13 are shown in place adjacent the end of the blank in Figs. 10 and 11. Fig. 12 is a sectional view showing one step in the formation of the leg, which consists in turning over the beaded edge, and Fig. 13 shows a further step which consists in giving the leg 75 and the reinforcing plates the angular bend to form the foot portion of the leg. Fig. 14 80 is a longitudinal sectional view illustrating the finished shape of the leg and the reinforcing means after the structure has been put through the dies in the usual manner. Instead of bending or rolling the edge as 85 shown in Fig. 12, it may be turned over against the reinforcing plate in the manner illustrated at 4^a in Fig. 15.

Although I have shown reinforcing plates secured in place in a specific manner, it will 90 be understood, of course, that they may be held in different ways while being shaped, and permanently secured to the leg in various ways; all of which is within the scope 95 of my invention. In some instances the 95 plates may be partially riveted before the leg is finished.

In some instances the leg may stop at the 100 foot portion, and the foot may be formed independently; in some instances wholly by reinforcing plates secured to said leg in substantially the manner illustrated in the other views of the structure, and in other instances by separate pieces secured to said reinforcing plates.

105 I claim:

1. The combination with a shaft hanger element of pressed sheet metal comprising a leg and a foot thereof, of reinforcing means made of pressed sheet metal and disposed at the point of junction between said leg and foot, said reinforcing means following the contour of said leg and foot and contacting therewith throughout its length and being additionally reinforced by a rib 115 formation in the leg and foot and the reinforcing means.

2. In a shaft hanger of pressed sheet metal, the combination with a leg and a foot thereof, of reinforcing means comprising a 120 plurality of similarly shaped plates disposed at the point of junction between the leg and foot, said reinforcing plates following the contour of said leg and foot and contacting therewith throughout its length and being 125 additionally reinforced by a rib formation in the leg and foot and the reinforcing plates.

3. In a shaft hanger, a leg and foot integrally connected, said members having 130

continuous beaded edges, and a reinforcing plate at the junction of said foot and leg confined in place by said beaded edges.

4. In a shaft hanger, a leg and foot integrally connected, said members having continuous beaded edges, and a plurality of reinforcing plates at the junction of said foot and leg confined in place by said beaded edges.

10 5. In a shaft hanger of pressed sheet metal, the combination of a leg, a foot, said leg having rolled edges, reinforcing means at the junction of the foot and leg engaged and retained by said rolled edges, and means for securing said parts in rigid relationship.

20 6. In a shaft hanger of pressed sheet metal, the combination of a leg, a foot integral therewith, said leg and foot having rolled edges, reinforcing means at the junction of the foot and leg engaged and retained by said rolled edges, and rivets for securing said parts in rigid relationship.

25 7. In a shaft hanger of pressed sheet metal, the combination of a leg, a foot, said leg having rolled edges, reinforcing means at the junction of the foot and leg retained by said rolled edges, and supplemental means for securing said parts in rigid relationship.

30 8. In a shaft hanger of pressed sheet metal, the combination of a leg, a foot integral therewith, said leg and foot having rolled edges, reinforcing means at the junction of the foot and leg retained by said rolled edges, and supplemental means for securing said parts in rigid relationship.

35 9. In a shaft hanger of pressed sheet metal, the combination of a leg, a foot, said leg having rolled edges, a plurality of reinforcing members at the junction of the foot and leg retained by said rolled edges, and rivets for securing said parts in rigid relationship.

40 10. In a shaft hanger of pressed sheet metal, the combination of a leg, a foot integral therewith, said leg and foot having rolled edges, a plurality of reinforcing members at the junction of the foot and leg retained by said rolled edges, and rivets for securing said parts in rigid relationship.

45 11. In a shaft hanger of pressed sheet metal, the combination of a leg, a foot, said leg having rolled edges and a centrally disposed longitudinal rib, reinforcing means at the junction of the foot and leg retained by said rolled edges, and supplemental means for securing said parts in rigid relationship, said foot and the reinforcing plates engaging the same having a depression in line with the rib of said leg.

50 12. In a shaft hanger of pressed sheet metal, the combination of a leg, a foot integral therewith, said leg and foot having rolled edges, reinforcing means at the junction of the foot and leg retained by said rolled edges, and rivets for securing said parts in rigid relationship, said foot and the reinforcing plates engaging the same having a depression in line with the rib of said leg.

55 13. In a shaft hanger of pressed sheet metal, the combination of a leg, a foot, said leg having rolled edges and a centrally disposed longitudinal rib, a plurality of reinforcing members at the junction of the foot and leg retained by said rolled edges, and rivets for securing said parts in rigid relationship, said foot and the reinforcing plates conforming to the same contour.

60 14. In a shaft hanger of pressed sheet metal, the combination of a leg, a foot, said leg having rolled edges and a centrally disposed longitudinal rib, a plurality of reinforcing members at the junction of the foot and leg retained by said rolled edges, and rivets for securing said parts in rigid relationship, said foot and the reinforcing plates engaging the same having a depression in line with the rib of said leg.

65 15. The combination with a shaft hanger element of pressed sheet metal including a leg and a foot for the same, of sheet metal reinforcing means disposed at the point of junction between said leg and foot, said reinforcing means following the contour of said parts at their junction and being additionally reinforced by a rib formation which includes the leg and foot.

70 16. The combination with a shaft hanger element of pressed sheet metal including a leg and a foot integral with the same, of reinforcing means formed of a plurality of sheet metal plates disposed at the point of junction between said leg and foot, said plates following the contour of said parts at their junction and being additionally reinforced by a rib formation which includes the leg and foot.

75 17. The combination with a shaft hanger element of pressed sheet metal including a leg and a foot, said structure having turned-over marginal edges, of independent reinforcing means at the junction of the foot and leg, and means for securing said parts in rigid relationship, said parts being additionally reinforced by a rib formation in the leg, foot and reinforcing means adjacent the junction of said leg and foot.

80 18. The combination with a shaft hanger element of pressed sheet metal including a leg and a foot integral therewith, said structure having turned-over marginal edges, of independent reinforcing means at the junction of the foot and leg engaged and retained by said turned edges, and means for securing said parts in rigid relationship, said parts being additionally reinforced by a rib formation in the leg, foot and reinforcing means adjacent the junction of said leg and foot.

85 19. The combination with a shaft hanger element of pressed sheet metal including a leg and a foot integral therewith, said structure having turned-over marginal edges, of independent reinforcing means at the junction of the foot and leg engaged and retained by said turned edges, and means for securing said parts in rigid relationship, said parts being additionally reinforced by a rib formation in the leg, foot and reinforcing means adjacent the junction of said leg and foot.

means adjacent the junction of said leg and foot.

19. In a shaft hanger of pressed sheet metal, the combination of a leg, a foot, sheet

5 metal reinforcing means at the junction of said leg with its foot, means for confining said reinforcing means in relative position with respect to the leg and foot, and means for securing the parts in rigid relationship.

10 20. In a shaft hanger of pressed sheet metal, the combination of a leg, a foot integral therewith, said structure having turned edges, sheet metal reinforcing means at the junction of the leg and foot, said

15 turned edges engaging the reinforcing means in relative position with respect to the leg and foot, and means for securing the parts in rigid relationship.

21. The combination with a shaft hanger

20 element made of sheet metal including a leg and foot, of reinforcing means disposed at the point of junction of said leg and foot, said reinforcing means following the contour of said leg and foot and contacting therewith throughout its length and being additionally reinforced by a rib formation common to the leg, foot and reinforcing means.

22. In a shaft hanger of sheet metal, the

30 combination with a leg and a foot thereof disposed at an angle with respect to each other, of a plurality of reinforcing plates disposed at the junction of the leg and foot, said reinforcing plates following the contour of said leg and foot with one of the same in contact therewith throughout its length, said structure being additionally reinforced by a rib formation common to the leg, foot and reinforcing plates.

40 23. In a shaft hanger of sheet metal, the combination of a leg, a foot, said leg having rolled edges throughout its length, reinforcing means at the junction of the leg and foot and following the contour of the same, and

45 means for securing said reinforcing means to the leg and foot, a portion of said rolled edges overlying the edges of the reinforcing means.

24. In a shaft hanger of sheet metal, the

50 combination with a leg and a foot thereof, of reinforcing means disposed at the junction of and following the contour of the leg and foot, means for securing said reinforcing means in rigid relationship with the leg

and foot, the marginal edges of said leg and foot being outwardly turned or rolled to overlap the reinforcing means, and the turned edges of said leg extending substantially throughout its length.

25. In a shaft hanger of sheet metal, the

60 combination of a leg, a foot, reinforcing means at the junction of the leg and foot, and means for securing said reinforcing means to the leg and foot, said leg having turned or rolled edges throughout its length

65 with a portion overlapping the edges of the reinforcing means.

26. In a shaft hanger of sheet metal, the combination of a leg, a foot, said leg having turned or rolled edges and being grooved

70 longitudinally to form an upstanding rib, and reinforcing means at the junction of the leg and foot, said reinforcing means being engaged by the rolled edges of the leg.

27. In a shaft hanger, a sheet metal leg

75 having a foot integral therewith, reinforcing plates extending from said leg into the foot and constituting an element thicker than the leg body, said foot being apertured through said reinforcing plates for the passage of retaining bolts, and means for rigidly securing said reinforcing plates to the leg and foot.

28. In a shaft hanger, a sheet metal leg

85 having a longitudinal rib substantially centrally disposed, and inturned beaded edges flanking said rib, a foot, and a plurality of reinforcing plates connecting said leg and foot and underlying said beaded edges.

29. In a shaft hanger, a leg and foot of

90 pressed sheet metal, said members having inwardly disposed beaded edges, and reinforcing means disposed at the junction of said foot and leg and confined in place by said beaded edges.

95 30. In a shaft hanger, a leg and foot of pressed sheet metal, said members having inwardly disposed beaded edges, and a plurality of reinforcing plates at the junction of said foot and leg and confined in place

100 by said beaded edges.

In testimony whereof, I have signed my name to this specification, in the presence of two subscribing witnesses.

GEORGE C. NOROS.
